UNITED STATES PATENT OFFICE

JACOB TELLER AND ARTHUR P. SCHULZ, OF NEW YORK, N. Y., ASSIGNEES TO TELLER CORPORATION, OF CHATTANOOGA, TENNESSEE, A CORPORATION OF TENNESSEE

DESIGN FOR A GAS OR ELECTRIC COOKING RANGE OR SIMILAR ARTICLE

Application filed November 2, 1931. Serial No. 41,601. Term of patent 14 years.

To all whom it may concern:

Be it known that we, JACOB TELLER and ARTHUR P. SCHULZ, citizens of the United States, and residents of New York city, in the county of New York and State of New York, have invented a new, original, and ornamental Design for a Gas or Electric Cooking Range or Similar Article, of which the following is a specification, reference being had to the accompanying drawings, forming a part thereof.

Figure 1 is a front perspective view of the range showing our new design;

Figure 2 is a similar view with the cover raised to expose the burner top;

Figure 3 is a front elevation; and

Figure 4 is a side elevation.

We claim:

The ornamental design for a gas or electric cooking range or similar article, as shown.

JACOB TELLER.

ARTHUR P. SCHULZ.
